UNITED STATES PATENT OFFICE.

EDWIN A. ARMSTRONG, OF DETROIT, MICHIGAN.

ROCK-DRILL.

SPECIFICATION forming part of Letters Patent No. 258,623, dated May 30, 1882.

Application filed September 14, 1881. (No model.)

To all whom it may concern:

Be it known that I, EDWIN A. ARMSTRONG, of Detroit, Wayne county, Michigan, have invented an Improvement in Rock-Drills, of 5 which the following is a specification.

The nature of this invention relates to certain new and useful improvements in the construction of rock-drills which are operated by hand; and the invention consists in the construction, arrangement, and combinations of 10 the various parts, all as more fully hereinafter described.

Figure 1 is an elevation. Fig. 2 is a vertical central section. Fig. 3 is a plan view. Fig. 4 15 is a horizontal section on line *xx*, Fig. 1. Fig. 5 is a horizontal section on line *yy*, Fig. 1. Fig. 6 is a plan of trunnion-head. Fig. 7 is a detached elevation of one tripod head and leg. Fig. 8 is a detail of double feed-pawl.

20 In the accompanying drawings, which form a part of this specification, A represents the drill-stock, in the lower end of which is removably secured the drill B, which may be of any of the known constructions. This drill- 25 stock is adapted to have a vertical reciprocating motion in the line of the axis of the frame C, and terminates at the upper end in a head, D, by which the drill receives its upward impulse through the medium of the cams E. 30 These cams are secured upon the shaft F, journaled in proper bearings G on top of the frame C, and are actuated by means of the hand-wheel H, which is provided with an adjustable crank-handle, I. The downward impulse or 35 stroke of the drill-stock is produced by a spring, J, coiled around the drill-stock in the lower tubular portion of the frame C, and is confined therein by the projecting shoulder *a* on the drill-stock and the shoulder *b* on the head of 40 the frame. The drill is partially rotated by the rotation of the drill-stock in the desired degree by means of the ratchet-wheel, K, pawl L, and cam M. The ratchet-wheel is feathered upon the drill-stock A, is confined in a recess 45 in the head of the frame C, and is provided with ratchet-teeth upon its face and upper side, a pawl, c, preventing its retrograde movement, while its advance is effected by the pawl L, attached to the bell-crank lever N, which in 50 turn is actuated by the double cam M, which for mechanical reasons is formed as an inte-

gral part of the shaft F. The pawl L operates through a slot in plate f, which incloses the ratchet-wheel in its recess. A thumb-screw, h, (shown in Fig. 5,) threaded through the upper portion of the frame, is provided with a stop, i, which comes in contact with the pawl-bearing arm of the bell-crank lever and admits of an adjustment to such lever, so that the drill-stock may be rotated in any desired degree. 55

The feed of the drill is effected by means of the screw O, tapped through the tripod-head P. The frame C, which carries all the operating parts of the device, is enabled to have the necessary reciprocating movement through the head P, and to guide it properly two opposite sides thereof are provided with the vertical feathers *g'*, which slide in corresponding grooves in the head. (See Fig. 6.) Thus, the 60 turning of the screw O will raise or lower the frame C with its attachments. 65

The feeding mechanism consists of the ratchet-wheel Q, pawls *k k'*, bell-crank lever R, and cam M', operating in substantially the same 70 manner as the mechanism described for turning the drill-stock. A thumb-screw, l, arranged and operating in the same manner as thumb-screw h, before described, allows of the desired adjustment of the feed, which is still 75 brought to a finer degree of adjustment by using double pawls *k k'*, arranged as in Fig. 8. To reverse the feed, a hand-wheel, T, is made to engage by proper gearing with the wheel Q, which also allows the feeding to be done by 80 hand, if desired. Should the feed not be effected in the necessary degree, the shoulder *a* will come in contact with the rubber cushion 85 *m* and indicate that more feed is required.

The tripod-head P, which guides and carries 90 the frame C and its operating parts, is provided with trunnions *n n'*. Clamped upon one of these trunnions are the secondary trunnions *o*, upon each of which a tripod-leg is removably secured. One of these legs is shown in 95 elevation, Fig. 7, and consists of the head *p* and two telescopic legs, *q r*, the latter of which is removably attached to the head by a ball-and-socket joint. Three of the four legs thus obtained are used as an ordinary tripod, while 100 the other may be employed, when necessary, for steadyng the drill laterally; or when the drill

is used in a horizontal position its ball is made to enter one of the sockets *s* of the trunnions *n* or *n'* to brace the drill against the roof, and it is for that purpose provided with a screw-ex-
5 tension, *t*, which allows of its being firmly ad-
justed to place.

It will be seen that the tripod can be used in-
terchangeably upon either of the trunnions *n* or *n'*, as the case may require.

10 What I claim as my invention is—

1. In a rock-drill, the frame *C*, in combina-
tion with the drill-stock *A*, the spring *J*,
adapted to give said drill-stock its downward
movement, the ratchet-wheels *K Q*, screw *O*,
driving-shaft *F*, and connections, substantially
15 as described, between the driving-shaft and
the ratchet-wheels, as and for the purpose
specified.
2. In a rock-drilling machine, the main shaft
20 *F* and cam *M'*, rotating with said shaft, in com-
bination with the pawl and lever *L N* and the
ratchet-wheel *K* and the drill-stock, for the pur-
pose of automatically and intermittently rotat-
ing said drill-stock, substantially as described.
- 25 3. In a rock-drilling machine, the main shaft
F and cam *M*, rotating with said shaft, in com-
bination with the pawl-lever *R*, the ratchet-
wheel *Q*, and the screw *O*, for the purpose of
automatically and intermittently advancing
30 the frame supporting the operating parts, sub-
stantially as described.

4. In a rock-drill, a tripod-head provided
with trunnions *n n'*, in combination with the
secondary trunnions *o*, adapted to be clamped
upon either of the trunnions *n n'*, and the ad-
justable legs *q r*, substantially as described. 35

5. In a rock-drill, a tripod-head provided with
two trunnions, *n n'*, each having an end socket,
s, in combination with the leg *r*, having an ad-
justable ball-head, *t*, whereby the tripod-head 40
can be clamped in a horizontal position, sub-
stantially as and for the purpose specified.

6. In a rock-drill, the case *C*, supported on
the trunnions *n n'* and legs *q r*, and the drill-
stock *A* and spring *J*, operating in said case, 45
in combination with the head *D*, the cams *E M*
M', arms *R N*, pawls *k L*, ratchet-wheels *K Q*,
and the screw *O*, as and for the purpose speci-
fied.

7. In a rock-drill, the shaft *F*, provided with
the cam *E* for retracting the drill-stocks, and
with cams *M M'* for feeding and rotating said
drill stock, in combination with intermediate
mechanism, substantially as described, between
the cams and the drill-stock and drill-frame, 50
as set forth.

In testimony that I claim the above I here-
unto set my hand.

EDWIN A. ARMSTRONG.

In presence of—

H. S. SPRAGUE,
E. I. SCULLY.
